WIRE BOUND PACKAGE

Jack W. Simmons, Tallahassee, Fla.

Application March 9, 1936, Serial No. 67,971

2 Claims. (Cl. 217—47)

This invention relates to the art of loose co-
erage, it being particularly concerned with col-
lapsible packages such as knockdown boxes, crates
and the like. In this art the wire bound pack-
age has come into wide use, the most common
types of such packages consisting of a unit made
up of a bottom and two side walls connected in
loosely hinged relation by flexible binding ele-
ments attached to and extending over their outer
faces at spaced intervals, together with a sepa-
rately attachable top or lid, and separately at-
tached end panels detachably associated with the
bottom and sides. The art has long sought an
assembly whereby the detachable end panels may
be applied with ease and speed yet without
sacrifice of strength.

An object of the present invention is the pro-
vision of a novel detachable panel assembly for
collapsible packages which eliminates the use of
tongues, grooves, and guide cleats, thus avoid-
ing in assembly the time consuming factor of
frictional resistance yet at the same time retain-
ing the structural strength of such means. Other
objects will be apparent from the description to
those skilled in the art.

The present disclosure constitutes a practical
embodiment by which the invention is reduced
to practice. It is to be understood that the struc-
tural details thereof are capable of variation as
desired so long as they remain consistent with
the scope of the invention as claimed.

In the drawing, Figure 1 is a perspective view
of a package embodying the invention.

Figure 2 is a perspective view of one of the
detachable end panels employed.

Figure 3 is a bottom plan view of a lid mem-
ber.

Figure 4 is an enlarged transverse vertical sec-
tion through an assembled package as in service
position.

Figure 5 is a section taken on the line 5—5
of Figure 4.

This invention finds perhaps its greatest field
of utility in connection with wire bound wooden
boxes and the like comprising a unit consisting
of a bottom B and opposed side walls W con-
nected in loosely hinged relation by flexible bind-
ing elements S, commonly wire straps, stapled
or otherwise suitably attached to the outer faces
of the walls and bottom at spaced intervals, par-
ticularly at the ends. The walls and bottom are
usually of slatted construction having bottom
end cleats 6 and side wall end cleats 7, the re-
spective ends of all the cleats being formed for
mortise and tenon engagement. By such ar-

rangement the walls may be folded outwardly
and downwardly with respect to the bottom for
collapsing. Associated with this unit is a lid mem-
ber L provided with cleats 8 at each end arranged
for mortise and tenon engagement with the tops 5
of the wall cleats, and having similar flexible
binding elements S secured thereto as short sec-
tions adapted to be tied to the ends of the bind-
ing elements on the foldable unit when in service
position, as shown at the top of Figure 4. 10

In practising the invention the wall cleats 7
are provided at vertically spaced intervals on
their inner faces with inwardly extending headed
securing studs having their shanks 9 anchored
in the bodies of the cleats and projecting lat- 15
erally inward therefrom, terminating in button
heads 10. End panels 11 are provided, they being
of proper dimensions to provide complete end
coverage. These end panels preferably have plane
inner faces and have secured to their outer faces 20
along each side edge portion a cleat 12 adapted
to abut the wall cleats 7 in registry therewith.
Extending through the material of the panels
and the panel cleats are key-hole slots having
their narrowed portions upwardly directed with 25
respect to the top of an assembled package, these
slots being designated 13. They correspond in
number and location to the securing studs on
the wall cleats.

In assembling a package the collapsible unit 30
is unfolded and opened to bring the walls W
perpendicular to the bottom B with the end joints
of their cleats in engagement. The end panels
11 are then placed in a vertical position between 35
the package walls, between which they may be
moved freely, and are moved towards the pack-
age ends with the enlarged portions of the key-
hole slots 13 taking over the button heads 10
of the securing studs after which they are moved
down until their lower edges rest on the package 40
bottom, whereupon the narrowed portions of the
slots will have taken over the shanks of the se-
curing studs locking the package ends together
in a strong reinforced end assembly. The lid 45
member L is then applied and the ends of the
flexible binding elements tied, assuring against
vertical movement of the end panels.

I claim:—

1. A collapsible package comprising in combi- 50
nation, a foldable unit consisting of opposed side
walls and a bottom connected in loosely hinged
relation by attached flexible binding elements,
end cleats carried by the ends of said walls,
headed studs carried by and projecting laterally
inward of said cleats, detachable panels insert- 55

ible and movable between said walls when in service position, and said panels being provided with key-hole slots adapted to take over said studs for interlocking said panels with said wall end cleats.

5. 2. In a collapsible package having a bottom and opposed side walls connected in hinged relation, end cleats on the inner faces of said walls,

studs projecting laterally inward from said cleats and having enlarged heads spaced from the inner faces of the cleats, a panel freely slideable between said walls longitudinally of the package, and said panel having key-hole slots for interlocking engagement with said studs behind their heads.

JACK W. SIMMONS.
